UNITED STATES PATENT OFFICE

145,780

DESIGN FOR A TELEPHONE DESK STAND

Gerald Deakin, New York, N. Y., assignor to International Standard Electric Corporation, New York, N. Y., a corporation of Delaware

Application August 3, 1945, Serial No. 121,185

Term of patent 14 years

(Cl. D26—14)

To all whom it may concern:

Be it known that I, Gerald Deakin, a citizen of the United States, residing at New York city, in the county and State of New York, have invented a new, original, and ornamental Design for Telephone Desk Stand, of which the following is a specification, reference being had to the accompanying drawing, forming part thereof.

Figure 1 is a top plan view of a telephone desk stand showing my new design;

Figure 2 is a front elevational view;
Figure 3 is a side elevational view; and
Figure 4 is a rear elevational view thereof.

I claim:

The ornamental design for a telephone desk stand, as shown.

GERALD DEAKIN.
